(57) **CLAIM**

The ornamental design for a combined beverage mug and can holder, as shown and described.

DESCRIPTION

FIG. 1 is an assembled rear perspective view of the combined beverage mug and can holder;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a bottom plan view thereof;

FIG. 7 is a top plan view thereof; and,

FIG. 8 is an exploded rear perspective view, corresponding to FIG. 1, with the removable cup portion removed from the holder.

The broken lining of a beverage can is included for the purpose of illustrating the environment of the combined beverage mug and can holder and forms no part of the claimed design.
